UNITED STATES PATENT OFFICE

2,523,713

TIELESS CONCRETE MOLD

William E. Mortrude, Jr., Seattle, Wash.

Application July 10, 1946, Serial No. 682,695

3 Claims. (Cl. 25—131)

1

My invention relates to the building arts and improvements therein associating tieless concrete and cement mortar molds with the resultant wall formed thereby.

One object of my invention is to make provision for mold wall units in the form of a V, when viewed from the end, which when a plurality of the said units are placed on end, in an upright position, and placed in side to side contiguity, the parallel sides of the extreme diverging edges are in unattached adjacency with formation of a plural V wall of any reasonable height as from a floor to a ceiling.

The primary object of employing V mold wall units, when set up as a double wall with concrete filling space means between and with each independent V mold unit of one wall diagonally opposite another such V mold unit of the opposite wall, is to provide a self contained wall reinforcing measure. That is, by adoption of the V mold wall units pressure resistance is instituted by the wall when subjected to the weight of the concrete mass contained within. The resistance of the V mold wall preventing bulging at any point from the foot to the top thus completely dispensing with the tedious work and expense of tying the walls together by means of wires and bolts such as is customary in concrete wall construction.

A further object of my invention is the means for longitudinal self locking of each succeeding V wall unit, thus tying the entire wall together horizontally. This is accomplished by pointing inwardly the V unions adjacently unattached, thus the opposing right angle forces pressing upon each joined V securely holds them together with a force equal to the weight of the concrete column contained within the mold.

Other objects of my invention confines itself to the principle that any one V wall unit, because of its V section, is capable of standing upright without bracing or holding, and which applies also to a plurality of such V wall units when set up as a wall. This provides a special construction embodying new and useful means for assembling a wall and expedites erection procedures.

Another object is that the concrete wall so formed, because of its multiple V form, presents a wall of greater strength than a straight or flat wall, and for this reason the thickness of the wall may be greatly reduced. Because of the thinness of the concrete V wall, a special top plate, covering the width expanse of the wall, must be placed along the entire top of the wall for supporting and attaching joists.

A full disclosure of the foregoing objects are included in the following specification and accompanying drawings.

In the drawings:

2

Fig. 1 is a perspective view of a V concrete mold unit.

Fig. 2 is a top plan view of a plurality of V concrete mold units arranged in side to side contiguity with their parallel edges adjacently unattached.

Fig. 3 is a top plan view of two continuous plural V walls placed apart and opposite so that the V's of one are opposite the V's of the other and with the V walls parallel with concrete space between. Also showing top anti-spreading members arranged along the sides of the walls and held by transverse members.

Fig. 4 is a cut-away projected view, in vertical, of Fig. 3.

Fig. 5 is a cut-away perspective view of a plural V mold resting within a footing recess, with a concrete wall formed, with a portion of the V mold units removed exposing the V concrete wall.

Fig. 6 is a cut-away view showing the top side of a concrete wall with top plate bolted to the top. Fig. 7 is a top plan of Fig. 6. Fig. 8 is a side vertical elevation of Fig. 7, with wall resting in footing recess, and with joist-rafter resting on top plate.

Like references denote like parts thruout the drawings.

Reference 10 represents a V concrete mold wall unit with an apex 11 and with preferably universally parallel sides 12 and 13. V mold wall unit 10, being of V construction, has two sides 14 and 15 and diverging, and with square cut ends 16 and 17 so that any one such unit may stand upright unassisted, without holding or bracing.

A plurality of V wall units (Fig. 2) 10 are shown mounted upon a footing and plate 18 and indicates the unattached unions 19, 19, of 10, 10, at 12 and 13. This arrangement of V wall units 10 provides a convenience for erecting extemporeous walls without resorting to concrete, and in which case the unattached union 19 is attached.

The two walls 20 and 21 (Fig. 3), comprising a plurality of V wall units 10 are spaced apart at any prearranged dimension, such as the thickness of concrete wall 23. They are so placed that the sides of any V so occupied are parallel as 14 of 21 is parallel to 14 of 20 and 15 of 21 is parallel to 15 of 20. It is also to be noted that any V wall unit 10 of 21 and 10 of 20 are placed so that their opposite positions overlap each other half ways, diagonally, and in such a way that V apex 11 points outwardly and is directly opposite unattached union apex 19 which points inwardly. It is important that unattached adjacent unions 19 point inwardly due to the fact that when the weight of the column of concrete mass 22 enters the mold space 23, pressure is directed against 60 the inside surface of 14 of 20 and 14 of 21,

according to arrow F, and counter pressure against 15 of 20 and 15 of 21, at arrow F, thus resulting in a holding pressure upon the outer surfaces of unattached surfaces 12 and 13 at union 19. It will be seen that this principle provides a responsible means for tying the V mold wall units 10 together with a force equal to the weight of the concrete mass 22 at any point from the top 17 to bottom 16 and ties all V wall units 10 together in the horizontal wall system.

Provision is made for anti-spreading means of the V mold walls 20, 21, and is accomplished by placing the said mold walls in a recess 24 of footing 25 so that the apex points 11 touch the sides 26, 27, of 24, allowing for molding space 23, which is the wall thickness. On the top 17, wall spreading is prevented by means of transverse members 28 secured to parallels 29 which fit down over the sides and contact the V points 11 along the entire length of the top of walls 20, 21.

It will be seen from the constructional features of the associated V mold wall units 10, 10, 10, etc., and the anti-wall-spreading means at 16 and 17, that no further tying of the walls 20 and 21 is necessary. This becomes apparent when it is noted that any side 14 or 15, existing as they do in 90 degree angular relationship or any plus or minus of 90 degrees, serve as reinforcing units all of which comprise the walls 21 and 20. The reinforcing power of the multiple and contiguously placed V wall units 10 is such that their resistance to the weight of the concrete mass 22 is equal to the tensile strength of a wooden member of equal width placed at right angles to the said pressure. That is, if the side 15 or 14 of a V wall unit 10 is a standard two by eight plank, it will resist a pressure equal to the resisting power of the said plank if placed at right angles, or the resisting power of the total plural V walls 20, 21, is equivalent to a plurality of two by eights placed approximately five inches apart and at right angles to the force. Hence, and in accordance with tests, the V mold walls so constructed possess more than ample resistance to counteract and prevent bulging from the weight of the concrete mass 22 at any point from 16 to 17, thus doing away with the undesirable tying together of the walls 20 and 21 by wires and bolts. A V wall unit 10, having an angle of 90 degrees appears to be the more practical angle although any angle may be employed so long as that angle is designed to conform with the pressures to which it is to be subjected.

Attention is directed to the constructional principle involved in the plural V concrete wall formed by the mold walls 20 and 21. It inherits a tensile strength considerably superior to that of a flat wall, mass for mass. While the multiple V concrete wall is longer by twenty seven percent it is designed to contain one third less concrete mass. This concrete mass reduction is permissible because of the greater strength of this type of wall. The thickness of the V wall may be reduced to as low as forty percent of a flat wall and yet possess high strength.

The concrete wall 22, because of its lesser thickness than flat walls, and because of its width expanse, is provided with studs 30 at its upper edge upon which is bolted the plate 31, preferably of wood, but not necessarily so. 31 may be of plate iron in special cases. The plate 31 serves to protect the upper edge of 22 when joists 32 and rafters 33 are to be placed upon 31 to which they are secured.

The vacant space 34 of recess 24 is filled in with cement mortar of water proofing qualities when the V mold units 10 are removed from the wall 22 after setting.

Mold wall unit 10 may be made from any material suitable for the work. Also the design of the mold wall unit 10 may be deviated from the design indicated upon the drawings without altering the claims set forth. That is, the sharp 10 V points within the mold wall, which determines the shape of the wall, may be made with a considerable radius to a degree within the limits of a semicircle without losing its claim identity, and without deviating from the principle involved.

The description of my invention contained within the foregoing paragraphs is believed to bring out the vital principles involved and right is reserved to make changes within the limitations of those principles found in the following claims.

I claim:

1. In mold means adapted to form two opposed sides of a concrete mold cavity, two spaced apart rows of independent and separable mold units of V-shaped cross section, each mold unit comprising two diverging side walls with plane flat edge portions which are parallel to each other and parallel to a plane which bisects the angle between said two diverging side walls, the mold units in each row being positioned in upright edge to edge contiguous relation with the concave side of each mold unit facing toward the mold cavity and with each mold unit of each row offset a distance equal to substantially one half of its width relative to opposed mold units in the other row, whereby transversely opposed mold unit walls in the respective rows are parallel to each other and adjoining edges of mold units in the respective rows are offset relative to each other; and means external to the mold cavity supporting the mold units of the two rows against movement away from each other.

2. In mold means adapted to form two opposite sides of a concrete mold cavity, two spaced apart rows of independent and separable mold units of V-shaped cross section, each mold unit comprising two diverging side walls, the mold units in each row being positioned in upright edge to edge contiguous relation with the concave side of each mold unit facing toward the mold cavity and with each mold unit of each row offset a distance substantially equal to one half of its width relative to opposed mold units in the other row, whereby a mold cavity of zigzag cross sectional shape is provided between said two rows of mold units and whereby the outward pressure of soft concrete in the mold cavity will press the contiguous edge portions of said mold units firmly together; and means external to the mold cavity positioned at the top and bottom portions of said mold units supporting said mold units against outward movement.

3. In mold means adapted to form two opposite sides of a concrete mold cavity, two spaced apart rows of independent and separable mold units of V-shaped cross section, each mold unit comprising two diverging side walls provided with plane flat edge portions which are parallel to each other and parallel to a plane which bisects the angle between said two diverging side walls, the mold units in each row being positioned in upright edge to edge contiguous unattached relation with the concave side of each mold unit facing toward the mold cavity and with each 70 mold unit of each row offset a distance substan-

tially equal to one half of its width relative to opposed mold units in the other row, whereby a mold cavity of zigzag cross sectional shape is provided between said two rows of mold units and whereby the outward pressure of soft concrete in the mold cavity will press the parallel contiguous unattached edge portions of said mold units firmly together; parallel supporting bars positioned outwardly from said mold units adjacent the top ends thereof for engagement by the apex portions of said mold units; cross bars positioned above said mold units rigidly connecting said parallel bars; and mold unit supporting means providing two upwardly extending spaced apart shoulders positioned external to the mold cavity for engagement by the apex portions

of said mold units adjacent their bottom ends, said mold units being unsupported and free from tie means between said bars and said shoulders.
